UNITED STATES PATENT OFFICE.

CHARLES W. CURLE, OF SAN FRANCISCO, CALIFORNIA.

TYPE-LINE STICK.

1,272,631.

Specification of Letters Patent. Patented July 16, 1918.

Application filed April 6, 1917. Serial No. 160,174.

To all whom it may concern:

Be it known that I, CHARLES W. CURLE, a citizen of the United States, residing at San Francisco, in the county of San Francisco, State of California, have invented a new and useful Type-Line Stick, of which the following is a specification in such full and clear terms as will enable those skilled in the art to construct and use the same.

10 This invention relates to a stick for holding lines of type in such a position as to enable the top of the type line to be cut off to prevent smudging.

It will be understood by those skilled in 15 the art that where a line of type is produced in a line casting machine that nearly always there is a blank portion at each end of the line which is not occupied by letters and which is likely to produce a smudge of ink 20 on the paper at the ends of the lines of letters.

Heretofore it has been common to cut off 25 the top of such lines as were likely to smudge the paper by running such lines of type through a machine specially adapted to saw off a portion of such line. This is a very slow process since it necessitates the accurate placing of each separate line against the saw or other tool intended to cut off the 30 desired amount of material.

With the present machine, a considerable number of type slugs are assembled along- 35 side of each other in the stick, the ends projecting more or less according to the position of the type projecting from the top of the slugs, after which such of the type slugs have a portion of their tops cut off in one 40 operation as may require it.

After the slugs carrying the type have 45 been cut down at one end, they may be reversed in position and will then be cut down at their other ends, the height of the slugs being reduced about the thickness of the saw used at the ends of the slugs beyond 50 the projecting type.

An embodiment of the invention is shown in the drawings in which the same reference numeral is applied to the same portion throughout, but I am aware that there may 55 be modifications thereof.

Figure 1 is a plan view of a saw table having this stick applied thereto.

Fig. 2 is a plan view of the stick as it appears when resting upon the slidable 55 table,

Fig. 3 is an edge elevation of the stick as

it appears when turned to the position for cutting the tops of the several lines of type held thereby, and

Fig. 4 is a side elevation of the stick look- 60 ing toward the bottom of Fig. 2, a portion of the guiderails on the saw table being shown for the purpose of illustration.

Fig. 5 is a side elevation of one of the type slugs showing the portions removed 65 therefrom by the saw in dotted lines.

Fig. 6 is a front elevation partly in section of the saw table and type line stick showing the stick turned up in position to 70 dress type lines supported thereby, the position of the saw also being indicated, and

Fig. 7 is a sectional view of the saw table and type line stick showing the stick turned down parallel to the table in position to 75 assemble the type lines therein prior to drawing them down.

The numeral 1 represents a saw table hav- 80 ing guides 2 and 3 along which guides a slidable table 4 is movable. The table 4 is provided with a guiderail 5 at one edge against which objects may be placed when it is desired to cut them off square and at a distance from the guiderail 5, and adjacent the edge of the table which moves along the saw 6 is a block 7. The saw is mounted 85 upon the shaft 8 and driven from the pulley 9 in a well known manner.

The guiderail 5 and block 7 have holes 90 therein to receive pins 10 and 11 supported in four depending ears 12 to 15 inclusive, and said pins are forced outwardly by means of a spiral spring 16 bearing upon the washers 17 and 18 which are secured to said pins 10 and 11.

The object of the foregoing construction is 95 to enable the user to apply to or detach the stick from the slidable saw table 4. The stick comprises a plate 19 with an open groove 20 extending from end to end thereof, in which groove is a rod 21, one end of which bears upon a heavy spiral spring 22, and the other end of which passes into a hole in a lug 24 of a plate 25 secured on one end of the stick base.

A narrow flange 26 is provided at one edge 105 of the plate 19 to prevent the slugs assembled thereon from slipping off, while extending over the top of the flange 25, and at right angles thereto, is a plate 27, which plate is rigidly secured to the plate 25. The 110 plate 27 has a shallow depending flange 28 at one edge, which is deep enough to catch

the letters on the upper edges of the slugs, so the slugs will slide through as illustrated in Fig. 2 stopping with varying lengths projecting.

5   Mounted on the plate 19 is a slidable plate 28' which has a vertical flange 29, and said plate has two depending lugs 30 and 31, through which the rod 20 extends. A plate 32 is mounted on the rod 21 in a hole in the 10 plate 28 and a spring 33 always tends to hold the plate in the position shown in Fig. 2. Pivoted on the top of the plate 28 is a lever 34, said lever having a heel piece 36 capable of bearing upon the plate 32.

15   The object of the foregoing construction is to provide means whereby the flange 29 may be moved tightly against the slugs placed between said flange and the flange 25 after the slugs have been dropped down 20 to the position occupied in Fig. 2. After a number of slugs have been assembled on the plate 19 between the flanges 25 and 29, they are allowed to slide down until they occupy the position shown by the slugs in Fig. 2, 25 whereupon they are tightly locked in place by the lever 34, and when so locked the stick is turned up ninety degrees to the position shown in Fig. 3, whereupon the table is moved along past the saw and the top of 30 each slug is removed thereby eliminating the danger of the slug smudging the paper while being printed from.

Having thus described my invention, what I claim as new and desire to secure by Letters Patent of the United States, is as follows:—express reservation being made of permissible modifications:

40   1. A type holding stick comprising a plate, means to secure a series of lines of type thereon, a plate under which the lines of type extend and having means thereon to determine the amount of extension of each

line beyond the plate, and a saw against which the lines of type may be passed to remove a portion of said extensions. 45

2. A type holding stick comprising a flanged plate, a saw table to which said plate is pivotally secured, a movable plate having a flange adapted to secure a plurality of lines of type in the stick, a plate under which the lines of type may pass and having means to determine the amount of extensions of said lines beyond said last named plate, and a saw against which the lines of type may be passed to cut a portion of said extensions. 50

3. A type line holding stick comprising a flanged plate, means to hold a series of lines of type against the flanged plate, a plate extending across the flanged plate having means thereon for determining the position of the plurality of type lines therein, a saw table and pivotal means between the saw table and type line holding device whereby the type line holding device may be turned 60 65 90 degrees to cut off portions of the tops of each of the lines of type.

4. A type line holding device comprising a slidable saw table, a type line holding plate having a flange at one edge, a second plate extending at right angles thereto, and under which a series of lines of type may be passed, means to hold a series of lines of type against the flange on said type line holding plate, a pair of pivot pins for mounting the type holding stick upon a reciprocating saw table, whereby the stick may be rotated substantially 90 degrees to bring the uncut edges of the type bar into a given plane for the purpose of removing a portion 70 75 80 of each slug.

In testimony whereof I have hereunto set my hand this 30th day of March, A. D. 1917.

CHARLES W. CURLE.
